UNITED STATES PATENT OFFICE.

ANNA FOY, OF PASADENA, CALIFORNIA.

INVALID-LIFTING DEVICE.

Application filed April 25, 1925. Serial No. 25,810.

This invention relates to an invalid lifting device or straps for use in connection with a bed and it constitutes an improvement of the structure for the same general purpose disclosed in Letters Patent issued to me on Sept. 5th, 1916, for a bed attachment, #1,197,472.

It is aimed to provide in the present instance, a construction which has efficient support on the floor adjacent to the bed and which may also be clamped or attached to the bed.

Another object is to provide a novel means whereby the device is adjustable as to height, as to the width of a bed and also to tilt the strap.

Still further, it is aimed to provide novel means for securing and operating the strap.

Various additional objects and advantages will become apparent from a consideration of the description following taken in connection with accompanying drawings illustrating an operative embodiment.

In said drawings:—

Figure 1 is an elevation of the apparatus in connection with a bed; the side rails of the latter being shown in transverse section;

Figure 2 is a view taken at a right angle to Figure 1;

Figure 3 is a detail section through the strap operating means;

Figure 4 is a section taken on line 4—4 of Figure 1;

Figure 5 is a detail of the adjusting means of one of the uprights, and

Figures 6 and 7 are detail sectional views taken on the lines 6—6 and 7—7 of Figure 1 as indicated.

Like reference characters designate like or similar parts in the different views.

Referring specifically to the drawings, a bed is conventionally shown as at 10 of which 11 specifically designates the side rails of its frame and 12 the mattress and bedding.

Disposed at each side of the bed is a standard 13 consisting of a relatively long foot 14 and a hollow upright 15. The feet 14 are connected by a bar 16 in telescoping sections 17 and 18, extending respectively from the standard 13 and secured together in any adjusted positions according to the width of the bed, as by means of a spring leaf 19 formed by slitting one end of section 18. A rod 19^a is journaled in section

18 and has a cam 20 movable against said leaf by manipulation of a pedal 20^a so that said leaf will frictionally bind against the inner wall of section 17 and thus secure the sections together. Surrounding each of the standards 13 is a clamp frame 22 which has an extension 23 adapted to engage the inner surface of one of the rails 11 and to clamp the device rigidly thereto through the manipulation of a screw 24 carried by the clamp. This form of clamp may be of any desired type.

An invalid lifting and supporting strap as at 26, is disposed transversely of the bed and adapted to function similarly to that at 15 in the patent aforesaid. This strap may be of any appropriate width or material, for instance, fabric, rubberized fabric, leather or the like, and at one longitudinal edge intermediate its ends may be semi-circularly cut away as in my said patent.

Strap supports 27 are provided. Each support has a stem 31 adjustably telescoped in the adjacent upright or standard 15 and adapted to be secured in any desired vertical position by a spring leaf latch 32 (see Figure 5) having a lug 33 passing through an opening in the adjacent upright 15 and engaging any of a series of openings 34 in the stem 31. At the top of stem 31, a frame 35 is pivoted at 37. Each frame has an arcuate slot 28 through which a screw 29 passes and which is threaded to a head 36 on stem 31 so that the frames and strap may be adjustably tilted. Roller 49 has the ends of the strap secured thereto and are provided with trunnions 50 journaled in the arms of frames 35. One of the trunnions of each roller has a worm wheel 53 fastened thereto which is in mesh with worms 54 of operating shafts 55 journaled in bearing arms 56 of frames 35. Each shaft is operable by a hand crank 56.

Sections 16 and 18 are hinged at 16^a to the standards so as to fold against the same in order to occupy minimum space when knocked down. Also rod 19^a has a flexible section 19^b so that it may fold with section 18.

The device as described, is readily adjustable as to width and height through the manipulation of the pedal at 20^a and the latches 32. The patient lays across the strap and the strap at the desired time is elevated through the manipulation of one or both of the cranks 56 since the latter drives the

rollers 49. The strap may be tilted or inclined from the pivots 37 as described.

Various changes may be resorted to provided they fall within the spirit and scope 5 of the invention.

What is claimed is:—

1. A device of the class described having standards disposable at opposite sides of a bed, a strap for the lifting of the patient, 10 means supporting said strap vertically adjustable on said standards, a bar in telescopic sections extending from the respective standards, and means to secure the bar sections together at different adjustments corresponding to the width of the bed consisting of an expansive means on one section, 15 and cam means to move said means into frictional engagement with the other section.
2. A device of the class described having a lifting strap, means disposable at each side of a bed to support the strap, telescopic means extending from one of said means to the other of said means, means for permitting said telescopic means to fold 20

against the respective first mentioned means 25 when the device is in knocked down condition, means within one of the telescopic means operable to bind the same against the other telescopic means to thereby secure the telescopic means in adjusted positions, and 30 the last mentioned means having a hinged portion whereby it may fold with its respective telescopic means.

3. An invalid lifting device adapted to be attached to beds, comprising standards carrying lifting devices and adapted to be clamped to the side rails of beds, telescopic tubular members connecting said standards, the inner of said tubular members having an 35 expansive portion adapted to engage the outer member to hold the members in fixed relationship, a rod rotatably mounted in said inner member, and a cam on said rod to engage said expandable portion and move it into engagement with the outer member. 40

In testimony whereof I affix my signature.

ANNA FOY.
